PRESSER FOOT FOR SEWING MACHINES

Ralph E. Johnson, Mountainside, and Charles A. Kessler, Plainfield, N. J., assignors to The Singer Manufacturing Company, Elizabeth, N. J., a corporation of New Jersey

Application January 24, 1951, Serial No. 207,532

3 Claims. (Cl. 112—235)

1

This invention relates to sewing machine presser-feet and more particularly to a presser-foot which is adapted to be employed in the stitching of elastic material.

The present presser-foot was developed in an effort to overcome the puckering effect which is produced in elastic cloth, such as "nylon," when it is stitched with elastic thread. This puckering effect is produced in the work material by the thread which, due to its elastic nature, is stretched during the stitch-forming operation with the result that the tensioned stitches tend to gather the work material upon the completion of the sewing operation in a manner as illustrated in Fig. 2 of the accompanying drawings.

The foregoing object and others ancillary thereto have been attained by the provision of a novel presser-foot which functions in cooperation with the conventional type four-motion feed-dog, to stretch the elastic work material during its progress past the stitching area of a sewing machine so that when the stitches are formed in the work material the latter will be stretched to the end that the resulting stitched material will have no tendency to pucker.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the drawings,

Fig. 1 represents an end elevation, partly in section, of a stitch-forming and feeding mechanism of a sewing machine showing the improved presser-foot.

Fig. 2 represents an enlarged longitudinal sectional view through a pair of stitched plies of work-material and illustrating a puckered effect which is produced by a conventional sewing machine when elastic needle-thread is used in the stitching of elastic work material.

Fig. 3 represents an enlarged longitudinal sectional view through a pair of stitched plies of work material as produced on a sewing machine employing the present invention and utilizing elastic work material and elastic needle thread.

Fig. 4 represents an enlarged right side view, partly in section, of the presser-foot and feed-dog illustrated in Fig. 1.

Fig. 5 represents a sectional view taken substantially along the line 5—5 of Fig. 4.

2

Fig. 6 represents an enlarged sectional view taken substantially along the line 6—6 of Fig. 5.

Fig. 7 represents an enlarged sectional view taken substantially along the line 7—7 of Fig. 4.

In the embodiment of the invention selected for illustration, my improved presser device is shown applied to a sewing machine having a bed 10 and a head 11. Journaled below the bed 10 is a rotary hook 12 and the usual feed rock-shafts 13 and 14 which impart a four-motion movement to a feed-dog 15 through the medium of a feed-bar 16, in the usual and well known manner. Mounted upon the bed 10 is a conventional throat-plate 17 formed with slots 18 through which the feed-dog 15 operates.

Journaled for reciprocatory movement in the head 11 is a needle-bar 19 carrying an eye-pointed needle 20. Also journaled for a right line up and down movement in the head 11 is the usual spring-depressed presser-bar 21. For a more complete and detailed description of the sewing machine mechanism, reference may be had to the patent of Kaier No. 2,206,285, dated July 2, 1940.

The present invention comprises a presser-foot shank 22 which may be detachably secured at its upper end portion to the sewing machine presser-bar 21 in a conventional manner by means of a screw 23. Pivotally attached to the lower portion of the shank 22 by means of a horizontal pin 24 is a primary sole plate 25 having a forward toe portion 26, a rearward heel portion 27 and a needle-receiving aperture 28 disposed between such portions. Also pivotally carried upon the above noted horizontal pin 24 is a substantially L-shaped bell-crank lever or arm 29 whose horizontally disposed limb 30 has pivotally mounted thereon an auxiliary or secondary sole-plate 31 which is normally disposed directly in front of the primary sole-plate 25. A pin 32 pivotally secures the secondary sole-plate 31 to the free end portion of the limb 30. The vertically disposed limb 33 of the bell-crank lever is apertured as at 34 so as to receive a horizontally disposed post 35 rigidly carried upon and extending rearwardly from the presser-foot shank 22. Carried upon and adjustable lengthwise of the post 35 is a collar 36 which functions as an abutment for one end of a coil spring 37 whose other end engages a washer 38 carried by the post 35 and abutting against the bell-crank lever for the purpose of biasing the auxiliary sole-plate 31 toward the sewing machine throat-plate 17 and against the work which is designated by the numeral 39.

By adjusting the collar 36 lengthwise of the arm 35, by means of a set screw 40 carried by the

collar 36, the clamping force of the auxiliary or secondary sole-plate 31 may be varied. By referring to Figs. 1 and 4 it is to be understood that whenever the presser-bar 21 is raised off the work, by means of the conventional presser-bar lifting mechanism not disclosed herein, the upper limb 33 of the pivot arm 29 will engage an abutment member 32 so that the movement of the arm about its pivot pin 24 will be arrested. In a preferred form of the present invention, the primary sole-plate 25 is disposed directly over and in cooperative relation with the lower feed-dog 15 while the secondary sole-plate 31 is located forwardly of the feed-dog.

In utilizing the present device, the effective force of the spring 37 is adjusted by means of the collar 36 so that the secondary sole-plate 31 will forcibly engage the elastic work material 39 to the end that pressure is exerted upon the work between the throat-plate 17 and the auxiliary sole-plate 31. Thus, as the feed-dog 15 functions, in cooperation with the primary sole-plate 25, to advance the work 39 past the stitching area, the elastic work material 39 will be stretched in an area defined between the secondary and primary sole-plates. The stitches 41, therefore, will be formed in the work while the latter is in this stretched condition. However, since the elastic needle thread, designated by the numeral 42, is stretched in a conventional manner during the stitch setting operation, it is possible by properly adjusting the spring 37 to stretch the work 39 in a manner proportional to the thread stretch, so that the resulting stitched work will have no tendency to pucker when the thread and the work material resume their respective natural states. In this connection reference may be had to Fig. 2 which illustrates a longitudinal section through a piece of work material made up of upper and lower plies 43 and 44 which are secured together by means of lock-stitches consisting of an upper needle thread 42 and a lower bobbin thread 46 which have been concatenated together in the usual manner. In a conventional type of sewing machine the feed-dog and presser-foot function to feed the work-plies past the stitching area without stretching the plies an appreciable amount. However, a conventional type sewing machine does stretch an elastic needle-thread during the setting of the stitches with the result that when the stitching operation is complete and the work is clear of the presser-foot, the stitches will tend to gather or pucker the work as illustrated in Fig. 2. The present presser-foot, however, functions in cooperation with the four-motion feed-dog 15 to stretch the work plies 43 and 44 during their movement up to the stitching area so that, when the stitches are formed in the work-material, the latter will be stretched to the end that the resulting stitched material will have no tendency to pucker, for upon the completion of the stitching operation both the needle thread and the work material will tend to relax to their original static states. Since both the needle thread and the work have been stretched a proportional amount, both the thread and the work upon the completion of the stitching operation will relax a proportional amount, thereby to form a stitched work piece which is free of any tendency to pucker.

Having thus set forth the nature of the invention, what we claim herein is:

1. A sewing machine presser-foot comprising, a shank adapted for attachment to the presser-bar of a sewing machine, a primary sole-plate pivotally carried by said shank and including a toe portion and a heel portion and a needle aperture formed between such portions, an arm pivotally carried by said shank member and extending over the toe portion of said primary sole-plate, a secondary sole-plate pivotally carried upon one end portion of said arm and being disposed directly in front of the toe portion of said primary sole-plate, spring means acting upon said arm to bias the latter about its pivot and relative to said primary sole-plate, and means for varying the pressure of said spring means upon said arm.

2. A sewing machine presser-foot comprising, a shank adapted to have its upper end attached to the presser-bar of a sewing machine, a post secured to and extending laterally from an intermediate portion of said shank, a primary sole-plate pivotally carried by the lower end of said shank and including a toe portion, a heel portion and a needle aperture formed between such portions, a substantially L-shaped arm having the lower limb thereof pivotally carried by the lower end of said shank member so that such limb will normally extend over the toe portion of said primary sole-plate, the upper limb of said arm being apertured for receiving therein said post, a coil spring carried by said post and engaging said arm thereby to bias the latter about its pivot, means for selectively varying the pressure of said spring against said arm, and a secondary sole-plate pivotally carried by the end of the lower limb of said arm and being disposed directly in front of the toe portion of said primary sole-plate.

3. A sewing machine presser-foot comprising, a shank adapted to have its upper end attached to the presser-bar of a sewing machine, a post secured to and extending laterally from an intermediate portion of said shank, a primary sole-plate carried by the lower end of said shank and including a toe portion, a heel portion and a needle aperture formed in said sole-plate between such portions, a substantially L-shaped arm having the lower limb thereof pivotally carried by the lower end of said shank member so that such limb will normally extend over the toe portion of said primary sole-plate, the upper limb of said arm being apertured for receiving therein said post, a coil spring carried by said post and engaging said arm in a direction to bias the latter about its pivot, and a secondary sole-plate carried by the end of the lower limb of said arm and being disposed directly in front of the toe portion of said primary sole-plate.

RALPH E. JOHNSON.
CHARLES A. KESSLER.
